Inventor:

P. De Vries

United States Patent Office.

PETER DE VRIES, OF ADRIAN, MICHIGAN.

Letters Patent No. 70,975, dated November 19, 1867.

IMPROVED BOOT-TREE.

The Schedule referred to in these Letters Patent and making part of the same.

TO ALL WHOM IT MAY CONCERN:

Be it known that I, PETER DE VRIES, of Adrian, in the county of Lenawee, and State of Michigan, have invented a new and useful Improvement on Fine Boot-Trees; and I do hereby declare that the following is a full, clear, and exact description of the construction and operation of the same, reference being had to the annexed drawings, making a part of this specification, and to the letters of reference marked thereon, in which—

Figure 1 is a side view.

Figure 2, a sketch of the construction of the inside work.

Figure 3, a transverse section.

The nature of my invention consists of a fine boot-tree, constructed with the foot B and front piece A; fig. 1, solid, and made in one piece without joint, and having the foot B, with the front piece A, back piece C, of uniform thickness, say one and one-half inch thick, with the outer edges of the two latter rounded, the sides flat, as shown by the straight lines *d e* and *f g* in fig. 3; the toe dropped down, so as to leave the foot at an angle of about forty-five degrees, the bottom of the foot, from the ball *a* to the toe *b*, being nearly flat across, the corners slightly rounded, and having the shank S hollowing. The tree is to be supplied with one or any convenient number of centre-spreading keys, K.

It also consists of two spreading-screws, G and H, figs. 1, 2, and 3, one of which, shown at G, fig. 2, descends perpendicularly into the upper end of the front piece A, and strikes obliquely upon the back side of the metallic lever I, at the point *t*, and pressing it forward, throws the lower end of the elbow *n* against the spring *i*, which is thereby pressed against the key K, and causes a spreading of the lower portion of the tree.

The other spreading-screw, H, passes edgewise through the back piece C at the top, and strikes directly against the top end of the key K, and causes a spreading of the upper end of the tree. The whole is so constructed as to fit any sized boot.

Claim.

What I claim as my invention, and desire to secure by Letters Patent, is—

The combination of the front and foot A B, (made in one piece,) the back C, the spreading-key K, the lever I, elastic plate *i*, vertical screw G, and horizontal screw H, all arranged and employed in the manner and for the purposes set forth.

PETER DE VRIES.
